UNITED STATES PATENT OFFICE.

JOHN SCHREIBER, OF ST. LOUIS, MISSOURI, ASSIGNOR TO JOHN H. SCHREIBER, OF ST. LOUIS, MISSOURI.

CONVEYER.

Application filed November 9, 1921. Serial No. 514,040.

To all whom it may concern:

Be it known that I, JOHN SCHREIBER, a citizen of the United States, residing at the city of St. Louis and State of Missouri, have **5** invented a new and useful Conveyer, of which the following is a specification.

This invention relates to conveyers of a type for conveying persons by operatives, or for conveying operatives by persons for **10** whom work is to be performed.

An object of the invention is to provide an improved conveyer of the character and for the purpose mentioned.

In the embodiment of the invention **15** shown, the conveyer is one for conveying persons or customers for whom work is to be performed past operatives or servitors, although it will be readily understood that the principle of the invention is general and that **20** the operatives or servitors may be moved relative to the customers or persons being served.

The specific embodiment of the invention shown is one for use in a shoe polishing establishment where the customers are seated upon the conveyer and are thereby carried or conveyed past the operatives or servitors who successively perform different stages of the work. The embodiment of the invention **25** shown for illustrative purposes comprises foot rests upon which the feet of the customers are placed while the service is being rendered, and a stationary platform for covering the foot rests to prevent them from **30** interfering with customers while the latter are passing to or from the conveyer.

Another object of the invention is to provide an improved conveyer of the character and for the purpose last mentioned, in which **40** a number of persons may be served successively by a series of operatives or servitors who successively perform different stages of the work from the initial portion thereof to the final completion thereof.

Another object of the invention is to provide an improved conveyer system for use in shoe polishing establishments embodying the improvements mentioned and which, in addition, occupies a comparatively small **45** area of space and which also embodies numerous other features of advantage, all of which will become apparent from the following description, reference being made to the drawing, in which

Fig. 1 is a plan view of the invention. **55**

Fig. 2 is a vertical sectional view illustrating other features of the invention.

The establishment in which the invention is shown is designed and adapted for use as a shoe polishing establishment, and includes **60** a room or space having an entrance 1 of sufficient width to admit the customers without interference with each other or with the attendants. The entrance 1 opens into a waiting room 2 which is of sufficient area to **65** contain necessary or desirable equipment and any needed attendants while leaving room for the passage of the customers therethrough to the conveyer. The equipment of the room 2 may be of any desired character, **70** as for instance a cash box 3 and a drinking fountain 4, with space 5 for an attendant.

From the waiting room 2 an ascending stairway 6 leads to a platform 7 within the work room or service room containing the **75** conveyer.

As shown, the conveyer is in the form of an annular series of seats 8 supported for rotation in a horizontal plane. The mechanism for rotating the seats may be of any **80** approved type and, as shown, comprises a shaft 9 attached to the axis of the seat frame and journaled for rotation in a support 10. A gear 11 attached to one end of the shaft 10 **85** is rotated by a power driven gear 12 which, in turn, is operated by an appropriate motor or power device 13. A frame member 14 in connection with the seat conveyer has an annular track 15 operating upon rollers 16 carried by a stationary frame 17. In this way the conveyer may be held steady while in rotation, irrespective of the distribution of **90** the weight on the conveyer.

A number of bifurcated foot rests 18 are **95** pivotally supported by the conveyer frame and have roller equipped arms 19, the rollers of which operate against the irregular edge of the frame 17. The construction and arrangement is such that as the foot rests **100** approach the edge of the platform 7, the roller equipped arms on the foot rests pass to a shorter portion of the frame 17, thus permitting the ends of the foot rests to drop or lower and pass under the platform **105** 7. As the foot rests pass beyond the platform 7 the roller equipped arms of the foot rests pass onto longer parts of the frame 7,

thereby raising the ends of the foot rests to position to receive and to support the feet of the customer. From this it will be understood that the frame 7 is in the nature 5 of a stationary cam, the major portion of which is of long radius to support the foot rests in position to support the feet of the customer during the time that the customer is being carried or conveyed past the attendants or servitors. That portion of the cam device which is under the platform 7 is of short radius, permitting the foot rests to drop to their lower positions and pass under the platform. Thus, the foot rests are entirely 10 out of the way at the points at which the customer's pass to and from the conveyer. This wholly prevents the clothing of the customer from becoming caught on or entangled with the foot rests and renders 15 the conveyer entirely safe.

The attendants within the work room in which the conveyer operates may occupy the spaces 20 which are separated at sufficient distance to enable each attendant to complete 25 the stage of work assigned to him before the customer passes to the next attendant. The conveyer, however, is in constant operation so that it is unnecessary for any of the attendants to move from their proper 30 positions. As stated, however, the relationship may be reversed, and the workmen or attendants may be located on the conveyer while the customers are stationary. The work room may also be formed with 35 cabinets or lockers such, for instance, as a supply cabinet 21 and a clothes locker 22 for use by the workmen or attendants, or by others as desired.

From that portion of the platform 7 at 40 which the customers alight from the conveyer a descending stairway 23 leads to a space or room 24 bordered on one side by a counter 25 adapted to contain and to display merchandise such as cigars, candy, chewing gum, etc. Behind the counter a space 26 is provided for an attendant or other person. The room or space 24 is provided with an exit 27 and is separated from the entrance room 2 by a rail or baluster 28 45 which also divides the ascending and descending portions of the stairway. A space 29 is provided within the room or space 24 for an attendant such as a porter.

The wall of the work room may be utilized 50 to display advertisements or the like, and as shown, the wall is formed with a supporting space 30 to receive display cards and advertising cards.

From the foregoing it will be seen that 60 my invention obtains all of its intended objects and purposes in a highly efficient manner. The embodiment of the invention which I have chosen for purposes of illustration, is a simple one designed especially 65 for the uses mentioned, although it is per-

fectly plain that the use of the invention is by no means limited to the purposes stated. It is obvious that the invention may be applied to numerous uses and that the form and arrangement may be varied widely 70 without departure from the principle involved.

I do not restrict myself to the specific form or to the specific uses mentioned herein, or in any unessential particulars, but 75 what I claim and desire to secure by Letters Patent is:—

1. A conveyer for effecting relative movement between customers and attendants, comprising a conveyer for moving one class 80 of such persons past the other class, seats for the customers, footrests to support the feet of the customers in position for service, and mechanism for operating the conveyer.

2. A conveyer for effecting relative movement between customers and attendants, comprising a conveyer for moving one class 85 of such persons past the other class, mechanism for operating the conveyer, seats on the conveyer for the persons thereon, footrests 90 to support the feet of the customers in position for service arranged to automatically move out of the customers way after service is rendered, and a platform for use by the persons boarding the conveyer or alighting 95 therefrom.

3. A conveyer for conveying customers by a series of attendants, comprising a support, means for moving the support past the position occupied by the attendants, and a series 100 of footrests on the conveyer to support the feet of the customers in position for service.

4. A conveyer for conveying customers by a series of attendants, comprising a support, footrests thereon to support the feet of the 105 customers in position for service, means for moving the support past the positions occupied by the attendants, and a stationary platform for use by the customers in boarding and alighting from the conveyer.

5. A system of the character described, comprising a room having an entrance and an exit, a stationary platform at the entrance and the exit, a rotary conveyer supported in the room for rotation on a vertical axis 115 in position to be boarded by persons on the platform and to permit the persons thereon to alight on the platform, seats on the conveyer, and footrests to support the feet of the customers mechanically controlled to permit use of the platform without interference by the footrests.

6. A system of the character described, comprising a waiting room having an entrance, a stairway leading from the waiting 125 room, a platform at the top of the stairway, a rotary conveyer operating adjacent to the platform to receive and carry the customers, seats on the conveyer, footrests projecting beyond the side edge of the conveyer, spaces 130

around the conveyer for the attendants, an alighting platform, and a stairway descending from the alighting platform to an exit.

7. A conveyer for effecting relative movement between customers and attendants, comprising a conveyer for moving one class of such persons past the other class, mechanism for operating the conveyer, seats on the conveyer for the persons thereon, a platform for use by the persons boarding the conveyer or alighting therefrom, and foot rests supported by the conveyer and arranged to move under the platform to permit use of the platform without interference by the foot rests.

8. A conveyer for conveying customers by a series of attendants, comprising a support, means for moving the support past the positions occupied by the attendants, a stationary platform for use by the customers in boarding and alighting from the conveyer, a series of foot rests pivoted to the conveyer, and a device controlling the foot rests to support them in position for use by the cus-

tomer as the customer is carried past the attendants.

9. A system of the character described, comprising a room having an entrance and an exit, a stationary platform at the entrance and the exit, a rotary conveyer supported in the room for rotation on a vertical axis in position to be boarded by persons on the platform and to permit the persons thereon to alight on the platform, and a series of foot rests pivotally supported by the conveyer and arranged to move under the platform.

10. A system of the character described, comprising a waiting room having an entrance, a stairway leading from the waiting room, a platform at the top of the stairway, a rotary conveyer operating adjacent to the platform to receive and carry the customers, a number of foot rests pivotally supported by the conveyer and movable to and from positions for service and arranged to move under the platform to permit use of the platform to prevent interference.

JOHN SCHREIBER.
